UNITED STATES PATENT OFFICE.

SAMUEL C. HOEN, OF ST. PAUL, MINNESOTA.

LADDER.

1,412,179.

Specification of Letters Patent. Patented Apr. 11, 1922.

Application filed April 4, 1921. Serial No. 458,567.

To all whom it may concern:

Be it known that I, SAMUEL C. HOEN, a citizen of the United States, residing at St. Paul, in the county of Ramsey and State of Minnesota, have invented a new and useful Ladder, of which the following is a specification.

My invention relates to ladders of the kind having rungs or steps frictionally held 10 at any point on the ladder rails to which they are moved usually by the feet standing on them; and the object is to provide a ladder of said type with several improvements.

In the accompanying drawing:

15 Fig. 1 is a side elevation of my improved ladder and a plank supported upon its steps.

Fig. 2 is a front elevation of Fig. 1.

Fig. 3 is an enlarged rear view of the top portion of the ladder as on the line 3—3 in 20 Fig. 1.

Fig. 4 is an enlarged section on line 4—4 in Fig. 2.

Fig. 5 is an enlarged section on line 5—5 in Fig. 1.

25 Fig. 6 is a section on line 6—6 in Fig. 2.

Fig. 7 is a section on line 7—7 in Fig. 1.

Fig. 8 is a section on line 8—8 in Figs. 2 and 9, with the pail 50 omitted, the same as in Fig. 2.

30 Fig. 9 is a side view of a portion of the ladder showing a movable bracket held on it and supporting a paint pail.

Fig. 10 is a section on line 10—10 in Fig. 1 with many parts omitted.

35 Fig. 11 is a detail rear elevation of one of the sliding frames holding the steps of the ladder.

Fig. 12 is a top view of Fig. 11.

Referring to the drawing by reference numerals, 14, 14 designate the two parallel rails or uprights of the ladder; which have their upper ends secured together by a horizontal offset brace 15 and the lower ends secured in a horizontal foot piece 16 which projects 40 some distance beyond the rails and is further secured to the latter by an arched brace 17.

Each rail 14 is stiffened by a truss rod 18 extending through brackets 19 and having its ends secured at 20 upon the rear side of 50 the rail. When the ladder is leaning rearwardly it is supported by a prop 21 having its bifurcated top end pivoted at 22 to the angular offsets of the brace bar 15. Further down the prop is provided with an eye-bolt 23 carrying a long hook rod 24 and a short one 25. The longer rod is adapted to be

hooked into a hole in one of the lower brackets 19, as at 26 in Fig. 1 for holding the prop properly spread away from the ladder. The shorter hook 25 serves to hold the ladder 60 in folded position as will presently be more fully described.

The ladder may have several foot rests or steps, but I have shown only one step 27 on each rail. These steps being alike I need 65 describe only one of them. The step proper is preferably a channeled piece of sheet metal pivoted near one end on a horizontal pivot bar 28 of a slidable metallic yoke or frame composed of said pivot bar 28, its 70 arms 29, a lower horizontal bar 30 and two vertical flat bars 31.

Inserted in said metal frame is a metal plate 32 held in place by having two rigid fingers 33, 34 straddling the bar 30, and its 75 upper portion guided between the arms 29 of the frame. Said plate may move slightly to and from the rail when the step is swung above horizontal position, but if the step is down to approximately horizontal position 80 its cam shaped end 35 presses the plate against the front side of the upright and pulls the bars 31 against the rear sides thereof, thus clamping the frame so firmly to the upright that it cannot slip downward even 85 when loaded by one or more persons standing on it, or on a plank placed as 36 in Fig. 1 upon the steps.

37 is a very limber coil spring serving to hold the step down so it can not accidentally 90 flap upward and lose its grip on the upright.

When the operator, standing with one foot on each step, desires to raise the step and climb upward he lets a wire bail 38, which is pivoted to the step, engage over the toe 95 portion of his foot or shoe (see Fig. 4) and can thus raise one step at a time and walk up like he would any other ladder. When a plank is to be placed on a step as a scaffold the bail 38 is leaned forward out of the way 100 as in Fig. 1. In the latter view is also shown that the prop 21 may have its hook released and be swung as 21^a to any desired horizontal position to find support in stairways or similar places.

Upon the front of the lower part of the ladder I pivot at 39 the arms of a U-shaped supporting brace 40, upon which is slidably mounted a cross bar 41 (see Fig. 7) adapted when tilted to engage the brace 40 frictionally. Said bar or plate 41 has a downward projection 41^a carrying a rod 42 hav-

ing an eye 43 adapted to be placed on a hook 44 in the base 16. The upper portion of the plate 41 is formed with a horizontal wing 45 having three fingers 46, 47, 48 which keep in place a bow-shaped leaf spring 49 the function of which is to hold the plate 41 normally in frictional engagement with the brace and thereby hold the latter in supporting and bracing contact with the ground or floor on which the ladder stands, though the angle between the floor and the ladder may be much varied or the ladder may in some cases have to stand almost in vertical position.

15 In Fig. 9 is shown a paint pot 50 or other container which may be supported on a bracket 51 having a hook 52 and a pair of jaws 53 loosely embracing one of the uprights and adapted to engage it frictionally whenever the bracket is pressed downward by its own weight or of the pail suspended on it. To make the hooks or jaws 53 fit uprights of different sizes I make the bracket arm bifurcated at 54 and embrace it by a slidable ring 55 which may also be open in one side and have its ends drawn more or less together by a screw 56.

When the ladder is folded for storing or transportation the steps are folded upward as shown in dotted lines in Fig. 2. The leg 40 is also folded upward until its cross bar 41 bears with its end portions against the steps to hold them folded. In this position the parts are secured by the short hook 25 engaging the looped end of the brace 40 (see Fig. 2).

It will be noted that the pail hanger 51

has a gap 54^a and each step supporting frame has a gap 54^b as clearance for the brackets 19 and the ends of the truss rods 40 18 in removing and replacing over the top end of each upright said slidable parts whenever so desired for repair or other purposes.

What I claim is:

1. The combination with the lower front side portion of the uprights of a ladder having a horizontal base bar, of a U-shaped brace having its arms hinged to the ladder and its loop end adapted to be swung upward parallel to the uprights or downward as a support upon the floor or other surface on which the ladder stands, a cross bar slidable on the brace and having a downward projection, a brace rod arranged for hitching said projection to the base bar, and a spring acting on the cross bar to normally tilt it into frictional engagement with the brace it slides on, said brace rod tending to increase said frictional contact whenever it is subjected to pulling strain by the contact of the main brace with the floor.

2. The structure specified in claim 1, and friction held upwardly foldable steps normally projecting forward one from each upright of the ladder, said cross bar on the frontal brace being long enough to engage and hold the steps in folded position when the ladder is idle, and means for holding the frontal brace in said upwardly folded position.

In testimony whereof I affix my signature.

SAMUEL C. HOEN.
